UNITED STATES PATENT OFFICE

161,199

PAPER TOWEL ROLL HOLDER

Albert A. Perelman, Brooklyn, N. Y., assignor to Scott Paper Company, Chester, Pa., a corporation of Pennsylvania

Application May 23, 1949, Serial No. 2,817

Term of patent 14 years

(Cl. D4—3)

To all whom it may concern:

Be it known that I, Albert A. Perelman, a citizen of the United States, residing at Brooklyn, Kings County, New York, have invented a new, original, and ornamental Design for a Paper Towel Roll Holder, of which the following is a specification, reference being had to the accompanying drawings, forming a part thereof.

In said drawings:

Fig. 1 is a perspective view of a paper towel roll holder, showing my new design;

Fig. 2 is a top plan view;

Fig. 3 is a front elevational view; and

Fig. 4 is an end elevational view thereof.

I claim:

The ornamental design for a paper towel roll holder, as shown.

ALBERT A. PERELMAN.
